UNITED STATES PATENT OFFICE.

BERNARD WIGDER, OF NEWARK, NEW JERSEY.

DESIGN FOR COMBINED DISPLAY CARD AND GOODS CONTAINER.

Application filed February 15, 1922. Serial No. 719. Term of patent 3½ years.

To all whom it may concern:

Be it known that I, BERNARD WIGDER, a citizen of the United States, residing at Newark, in the county of Essex and State of New Jersey, have invented a new, original, and ornamental Design for Combined Display Card and Goods Container, of which the following is a specification, reference being had to the accompanying drawings, forming a part thereof.

In said drawing Figure 1 is a plan or face view of a combined display card and goods container showing my new design; and Figure 2 is a longitudinal edge elevation of the same.

I claim:—

The ornamental design for combined display card and goods container, as shown.

BERNARD WIGDER.
